LATCH CONSTRUCTION

Carl C. Fish, Detroit, and Clifford V. Johnson,
Pontiac, Mich., assignors to Ferro Stamping
and Manufacturing Company, Detroit, Mich., a
corporation of Michigan

Application July 2, 1945, Serial No. 602,780

6 Claims. (Cl. 292—65)

1

This invention relates generally to latch mechanisms and refers more particularly to vehicle body door latches of the pivoted bolt type.

One advantage of vehicle body door latches of the pivoted or rotary bolt type is that the bolt usually coacts with a striker to take up any slight shifting movement of the door relative to the surrounding framework and thereby eliminates one of the most common causes of door rattles. While this is a very desirable characteristic, nevertheless, it introduces the problem of overcoming the considerable force required to unlatch the door on occasions when the wedging pressure between the bolt and striker reaches excessive proportions.

The present invention overcomes the above objection by providing a latch mechanism wherein initial manipulation of the latch operating member relieves the wedging pressure between the bolt and striker prior to actually swinging the bolt to its released position. In accordance with the present invention, the bolt is supported in a manner to drop away from the striker upon initial movement of the latch operating member to release the latch. The arrangement is such that very little effort is required to release the latch bolt from the striker, even though the wedging pressure between the bolt and striker is exceedingly high.

The foregoing as well as other objects will be made more apparent as this description proceeds, especially when considered in connection with the accompanying drawings, wherein:

Figure 1 is a front elevation of a latch mechanism embodying the features of this invention;

Figure 2 is a side elevation of a part of the latch mechanism shown in Figure 1;

Figure 3 is a rear elevation of another part of the latch mechanism illustrated in Figure 1;

Figure 4 is a fragmentary sectional view through a part of the latch mechanism and showing the bolt in its operative position;

Figure 5 is a view similar to Figure 4 showing the bolt in its released position; and

Figure 6 is a sectional view taken substantially on the plane indicated by the line 6—6 of Figure 4.

The latch mechanism selected for the purpose of illustrating this invention is shown in the several figures of the drawings as comprising a plate 10 having sections 11 and 12 arranged at substantially right angles to each other. Supported on the outer face of the section 11 is a pivoted bolt 13 comprising two parts indicated in the drawings by the reference characters 14 and 15.

2

The part 14 is pivoted on the section 11 of the plate by means of a pin 16 and has an upwardly opening recess 17 in the upper end portion thereof. The part 15 forms the head of the bolt and is provided with a shank portion 18 which projects into the recess 17 of the part 14. The shank 18 slidably engages the walls of the recess to enable movement of the head 15 relative to the part 14 and the lower end of the shank is formed with a recess 19 to provide clearance for the pin 16. The top surface 20 of the head 15 is shaped to engage a striker indicated by the dotted lines in Figure 1 of the drawings and designated by the reference character 21.

15 A housing 22 for the bolt 13 is suitably secured to the front face of the plate 11 and is formed with an opening in the top wall through which the head 15 of the bolt projects. Attention is called to the fact that the top surface 20 of the head 15 on the bolt is arcuate in contour and the adjacent face of the striker 21 is correspondingly curved so that when the two surfaces are in contact, the door on which the latch mechanism is installed is securely held in its closed position. In actual use, when the bolt and striker are in the relative positions shown in Figure 1 of the drawings, any slight motion of the door or latch mechanism relative to the striker tends to increase the wedging engagement between the complementary curved faces of the bolt and striker 21. Thus, shifting movement of the door while in its closed position is ordinarily taken up and the door is firmly held in its closed position.

30 The bolt 13 is operated by a slide 23 supported on the rear face of the plate 11 for vertical sliding movement. The slide is guided throughout its travel by means of a pair of lugs 24 struck rearwardly from the plate 11 and respectively engageable with opposite side edges of the slide intermediate the ends of the latter. The upper end of the slide is attached to the plate by means of a pin 25 anchored on the plate 11 and projecting through a vertically elongated slot 26 formed in the slide 23. The rear end of the pin 25 is riveted over a washer 27, which in turn slidably engages the rear face of the slide 23 and holds the latter in position on the plate 11. The lower end portion of the slide 23 is attached to the head 15 of the bolt 13 by means of a pin 28, which projects through a slot 29 formed in the plate 11 and has the front end portion anchored in the head 15 of the bolt. The rear end of the pin 28 extends through an enlarged opening 30 formed in the slide 23 and is riveted over a washer 31 which engages the rear surface of the slide 23.

Upon reference to Figures 4 and 5 of the drawings, it will be noted that one wall 33 of the enlarged opening 31 in the slide 23 is inclined with respect to the vertical path of travel of the slide and acts as a cam face for engaging the adjacent side of the pin 28. The bottom wall 34 of the enlarged opening 30 engages the bottom side of the pin 28 to hold the bolt in its extended or operative position shown in Figures 1 and 4 of the drawings. In the above position of the bolt, the pin 28 is also in engagement with the lower portions of the wall 33 and the latter inclines upwardly in substantial tangential relation to the pin 28. This relative position of the parts is maintained by a spiral spring 35 having one end anchored to the rear wall of the plate 11 adjacent the lower end of the latter and having the opposite end engaging the bottom surface of the slide 23.

The slide 23 is moved downwardly against the action of the spring 35 by means of an operating handle 36 positioned at the outer side of the plate 12 and having a shank 37 projecting through the plate 12. In accordance with conventional practice, the shank 37 is connected to a roll-back 38 supported for rocking movement at the inner side of the plate 12 and engageable with a segment 39. The segment 39 is supported for rocking movement at the inner side of the plate 12 and is provided with a lug 40 positioned to engage a cooperating lug 41 on the vertical slide 23.

It follows from the above construction that rocking movement of the operating handle 36 effects a corresponding rocking movement of the roll-back 38 and the latter swings the segment 39 downwardly to engage the lug 40 thereon with the lug 41 on the slide 23. Due to the clearance provided between the top wall 42 of the enlarged opening 30 in the slide and the adjacent side of the pin 28, initial downward movement of the slide 23 is effected without actually swinging the bolt 13 about the pin 16. However, this initial downward movement of the slide 23 relieves the pin 28 from contact with the wall or cam 33 and enables the head 15 on the bolt to shift slightly in a downward direction relative to the part 14 of the bolt. As a result, the wedging action between the head of the bolt and striker is relieved so that this force need not be overcome by the operator when releasing the latch. Of course, continued downward movement of the slide 23 engages the top wall 42 of the opening 30 with the adjacent side of the pin and swings the bolt to its released position shown in Figure 5 of the drawings.

What we claim as our invention is:

1. A latch mechanism comprising a plate, a bolt having a part supported on the plate for swinging movement and having a head adapted to engage a striker with a wedging engagement, said head supported on the part for swinging movement as a unit with the part and for sliding movement relative to said part toward and away from the striker, a pin projecting laterally from the head, a vertically movable slide having an opening for receiving the pin, spring means normally urging the slide in an upward direction to engage the bottom and an adjacent side wall of the opening with the pin for holding the head part of the bolt in an extended position relative to the swinging part, said opening being larger than the cross-sectional area of the pin and the side wall aforesaid of the opening being inclined in a direction to relieve the pin

from engagement therewith upon initial movement of the slide in a downward direction to permit sufficient displacement of the head relative to the swinging part to relieve the wedging pressure between the bolt head and striker.

2. A latch mechanism comprising a supporting plate, a bolt having a part pivoted on the plate for swinging movement and having a head adapted to engage a striker with a wedging contact, said head being supported on the part for swinging movement as a unit with said part and for sliding movement relative to the part in directions toward and away from the striker, an operating member supported by the plate for movement in opposite directions, yieldable means acting on the operating member for urging the latter in one direction, cooperating engaging means on the bolt head and member operated by the yieldable means to yieldably maintain the bolt head into wedging contact with the striker, means for moving said member in a direction against the action of the yieldable means to disengage said surfaces and thereby relieve the contact pressure between the head and striker, and means responsive to continued movement of the operating member against the action of the yieldable means to swing said bolt out of engagement with the striker.

3. A latch mechanism comprising a supporting plate, a bolt having a part pivoted on the plate for swinging movement and having a head adapted to engage a striker with a wedging contact, said head being supported on the part for swinging movement as a unit with said part and for sliding movement relative to the part in directions toward and away from the striker, an operating member mounted on the plate for sliding movement in opposite directions in a plane substantially parallel to the plane of swinging movement of the bolt, spring means acting on the operating member for urging the latter in one direction, cooperating engaging surfaces on the bolt head and member coacting with the spring means to yieldably maintain the bolt head into wedging contact with the striker, means for moving the operating member in a direction against the action of the spring means to disengage said surfaces and thereby relieve the contact pressure between the bolt head and striker, and additional cooperating engaging surfaces on the operating member and bolt head engageable upon continued movement of the operating member in a direction against the action of said spring means to swing said bolt out of engagement with the striker.

4. A latch mechanism comprising a support, a swinging bolt having a part pivoted on the support for swinging movement and having a head adapted to engage a striker with a wedging contact, said head being supported on the part for swinging movement as a unit with said part and for sliding movement relative to the part in directions toward and away from the striker, an operating member mounted on the support for sliding movement in opposite directions, yieldable means acting on the operating member for urging the latter in one direction, cooperating engaging surfaces on the bolt head and member coacting with the yieldable means to yieldably maintain the bolt head into wedging contact with the striker, means including a rollback for moving the operating member in a direction against the action of the yieldable means to disengage said surfaces and thereby relieve the contact pressure between the bolt head and striker, and means responsive to continued movement of the operating

member in a direction against the action of the yieldable means to swing said bolt out of engagement with the striker.

5. A latch mechanism comprising a support, a swinging bolt having a part pivoted on the support for swinging movement and having a head adapted to engage a striker with a wedging contact, said head being supported on the part for swinging movement as a unit with said part and for sliding movement relative to the part in directions toward and away from the striker, an operating member mounted on the support for movement in opposite directions, yieldable means acting on the operating member for urging the latter in one direction, cooperating engaging surfaces on the bolt head and member coacting with the yieldable means to yieldably maintain the bolt head into wedging contact with the striker, means for moving the operating member in a direction against the action of the yieldable means to disengage said surfaces and thereby relieve the contact pressure between the bolt head and striker, and additional cooperating engaging surfaces on the operating member and bolt head engageable upon continued movement of said member in a direction against the action of the yieldable means to swing said bolt out of engagement with the striker.

6. A latch mechanism comprising a support having angularly related plates, a swinging bolt having a part pivoted on one plate for swinging movement in a plane substantially parallel to said one plate and having a head adapted to engage a striker with a wedging contact, said head being supported on the part for swinging movement as a unit with said part and for sliding
